The ornamental design for a dental suction unit, as shown and described herein.

DESCRIPTION

FIG. 1 is a perspective view of a dental suction unit;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom plan view thereof.
The broken lines depict portions of the dental suction unit that form no part of the claimed design.
